UNITED STATES PATENT OFFICE.

CARL S. WEYANDT, OF PITTSBURGH, PENNSYLVANIA, ASSIGNOR TO CENTRAL ELECTRIC TOOL COMPANY, OF PITTSBURGH, PENNSYLVANIA, A CORPORATION OF PENNSYLVANIA.

ELECTRIC-DRIVE MECHANISM.

Application filed November 20, 1919. Serial No. 339,323.

To all whom it may concern:

Be it known that I, CARL S. WEYANDT, a citizen of the United States, residing at Pittsburgh, in the county of Allegheny and 5 State of Pennsylvania, have invented certain new and useful Improvements in Electric-Drive Mechanisms, of which the following is a specification.

This invention relates to electric drive mechanisms, such as hammers, chipping tools, drills, calking tools, and the like, wherein a reciprocating element is employed for the production of work, and is designed primarily for electric hammers, although it 10 is to be understood that it is adapted for any purposes wherein it is found applicable, and the invention has for its object to provide a drive mechanism, in a manner as hereinafter set forth, including means to set up an electrical circuit at proper intervals of time through one solenoid for reciprocating an element, i. e., the solenoid core which constitutes a plunger, to impact a tool to operate the latter.

25 A further object of the invention is to provide an electric drive mechanism operated through the medium of a magnetic circuit having an air gap within the coil thereof, whereby the energy is concentrated at 30 the air gap and there is provided an outlet for passing the energy with minimum losses to the reciprocating element or the core of the solenoid constituting a plunger. This form of magnetic circuit gives a high power 35 factor and eliminates excessive heating while permitting the radiation surface of the coil to be reduced to a minimum.

40 A further object of the invention is to provide an electric drive mechanism operated through the medium of a magnetic circuit having an air gap within the coil thereof and to position the air gap in close proximity to the solenoid core or plunger, thereby reducing magnetic leakage.

45 A further object of this invention is to provide an electric drive mechanism whereby the reciprocating core of the solenoid is utilized to engage contacts to energize and de-energize the solenoid for the purpose of 50 changing the direction of travel of the plunger.

A further object of the invention, is to so arrange, in a manner as hereinafter set forth, the contacts, plunger, magnetic circuit and

air gap, that maximum acceleration of the 55 plunger is attained.

Further objects of this invention are to provide an electric drive mechanism, which is simple in its construction and arrangement, compact, strong, durable, having the 60 size thereof reduced to a minimum, convenient and efficient in its use, readily assembled and comparatively inexpensive to manufacture.

With the foregoing and other objects in 65 view the invention consists of the novel construction, combination and arrangement of parts herein specifically described and illustrated in the accompanying drawings, 70 wherein is shown an embodiment of the invention, but it is to be understood that changes, variations and modifications can be resorted to which come within the scope of the claims hereunto appended.

In the drawings forming a portion of this 75 specification and wherein like numerals of reference designate corresponding parts throughout the several views:

Figure 1 is a longitudinal sectional view of an electric drive mechanism made in accordance with this invention and showing the adaption thereof in connection with an 80 electric hammer.

Figure 2 is a diagrammatic view illustrating the arrangement of the electric circuits. 85

Figure 3 is a detail cross sectional view of the device.

Referring to the drawings in detail, where- 90 in the drive mechanism is illustrated, by way of example, in connection with an electric hammer, the casing of the mechanism is formed of any suitable material and com- 95 prises a head or handle portion, an end or tool receiving portion and an intermediate portion, but it is to be understood that the arrangement of the casing can be as desired. The end portion consists of a socket member 10, which receives the tool to be operated, and the member 10, has formed integral therewith and projecting therefrom a collar 11, which terminates in a flaring extension 12, provided with a shoulder 13, and internal threads 14. The head comprises a hollow conical shaped member 15, having a shoulder 16 and internal threads 17. The 100 member 15 is formed with a pair of openings 18 and 19, the former being of greater diameter than the latter. Formed integral

with the member 15 is a hollow handle 20 having the end thereof which is integral with the member 15 register with the opening 18. The wall of the opening 19 is 5 threaded and the handle 20 has an opening 21 with the wall of the latter threaded. Seated in the opening 19 is a plug 22 for the leading-in-wires, and mounted in the opening 21 is a push-button or switch 23. The 10 intermediate portion of the casing is formed of two spaced annular members 24', 25' which are connected together by a coupling band 26'. The member 24' engages with the threads 14 and the member 25' with the 15 threads 17. By the arrangement set forth the casing of the mechanism can be assembled and disassembled quickly when occasion so requires. The tool is not shown mounted in the member 10, but any form of tool, 20 which can be operated on, is employed.

Mounted in the casing of the mechanism is a longitudinally extending cylindrical tube 24 of non-magnetic material formed at its forward end with a pair of slots 25 and at 25 its rear end with a pair of slots 26. At the forward end of the tube 24, are pivotally mounted oppositely disposed spring controlled contacts 27, two in number, and which normally project through the slots 25, into 30 the tube 24, and in the path of the core of the solenoid, to be hereinafter referred to, said core forming the reciprocatory element of the mechanism and constituting the plunger which acts on the tool mounted on or 35 rather in the member 10. At the upper or rear end of the tube 24, are pivotally mounted oppositely disposed spring controlled contacts 28, two in number, which normally project through the slots 26, into the tube 24, 40 and in the path of the core of the solenoid referred to above.

Mounted on the tube 24, intermediate the ends thereof, is a solenoid consisting of the coil 29 and the core 30, the latter being the 45 reciprocatory element of the mechanism and constituting a plunger which reciprocates in the tube 24. Surrounding the coil 29 are C-shaped cores of laminated form, as indicated at 31. They are so shaped as to 50 provide air gaps 32 at that side thereof bearing on the tube 24. The cores 31 enclose the coil 29 and provide magnetic circuits formed with air gaps. The air gaps 32 are arranged around the central portion 55 of the tube or barrel 24 and may be regarded in effect as an annular gap. Within the tube 24 at the forward end thereof is arranged a coil spring 33 to take vibration off the handle 20 during the reciprocation of the core 60 or plunger 30.

The arrangement of the conductors for forming the circuit to provide for the reciprocation of the core or plunger 30 is as follows:—

65 The leading-in-wires are indicated at 1,

2, 3 and 4, and are carried through the casing of the mechanism in the plug 22. The wire 1 leads to one of the contacts 27 and the wire 4 leads to the other contact 27. The wire 2 leads to the coil 29, and the wire 3 70 to one of the contacts 28. Leading from the other contact 28 to the wire 4 is a wire 6. Leading from the switch 23 to the coil 29 is a wire 7 and leading from the switch 23 to the wire 4 is a wire 8.

75 The operation of the drive mechanism is as follows—

Associated with the drive mechanism is a magnetic switch including two pairs of contacts, the contacts of one pair are indicated at 34, and the contacts of the other pair 80 at 35. The arm 36 operated by the coil 38 carries the lower contact 34 and the arm 37 operated by the coil 39 carries the lower contact 35. The magnets 38 and 39 are connected together by a conductor 42, from which leads a conductor 43 to source. The wire or conductor 4 leads to source. The wire or conductor 2 leads to one of the contacts 35. The conductor 1 leads to magnet 90 39 and the conductor 3 leads to magnet 38. The conductor 43 is connected with the conductor 41.

95 It will be assumed that the plunger is in position, as shown in Figure 2, having contact engagement with the pair of contact arms 27, which complete an electrical circuit from the source of supply through conductors 4 and 1 and magnet 39. The magnet 39 being energized closes contacts 35 closing an 100 electrical circuit through conductors 2, 7, 8 and 4 and coil 29. The coil 29 now being energized induces a flux in the magnetic circuit whereby the plunger is drawn into the 105 air gap. The engagement between the plunger and contacts 27 is maintained until maximum acceleration has been imparted to the plunger, at which instant the contacts 27 are opened which opens contacts 35 and opens the circuit through the coil 29. The 110 plunger however due to kinetic energy passes to the other end of the tube 24 and engages contacts 28 thus making an electrical circuit from the source through conductors 3, 4 and 6, magnet 38 to source. The magnet 115 38 now being energized closes contacts 34 and energizes coil 29 through conductors 2, 7, 8 and 4 which pulls the plunger in the opposite direction until its engagement with the contacts 27 for the purpose heretofore 120 stated.

125 The plunger in its travel strikes against the tool, which may be a chisel, welding die or any other instrument upon which a blow may be used to produce work.

What I claim is:

1. In an electric hammer, current supply lines, a single solenoid, a magnetic core reciprocable therein, and contacts closable by the core at the end of each stroke of the 130

core to effect the next stroke, and openable by the core when the latter reaches the central part of the solenoid.

2. In an electric hammer, current supply lines, a single solenoid, a magnetic core reciprocal therein, and contacts closable by current through the core at the end of each stroke of the core to effect the next stroke, and openable by the core when the latter reaches the central part of the solenoid.

3. In an electric hammer, current supply lines, a single solenoid, a magnetic core reciprocal therein, contacts closable by current through the core at the end of each stroke of the core to effect the next stroke, and openable by the core when the latter reaches the central part of the solenoid, and switching means operated by current through said contacts and connecting the solenoid to the said lines.

4. In a reciprocating apparatus, a solenoid, means to provide a magnetic circuit provided with an air gap, said circuit co-acting with the solenoid, a core arranged to reciprocate through the solenoid to open

and close the gap thereby opening and closing the magnetic circuit, a switching element in circuit with the solenoid for causing the energization and de-energization thereof when the gap is closed and opened by the core, and means engaged by the core and in connection with the latter for closing an operating circuit to throw said switching element into operation during the reciprocation of the core.

5. In a reciprocating apparatus, a solenoid, means to provide a magnetic circuit co-acting with the solenoid, said circuit having an air gap, means to energize and de-energize said solenoid, and a core arranged to reciprocate through said solenoid for opening and closing said gap, said core during its reciprocations throwing said means for energizing and de-energizing the solenoid into and out of operation to alternately energize and de-energize said solenoid to cause reciprocations of the core.

In testimony whereof I affix my signature.

CARL S. WEYANDT.
